UNITED STATES PATENT OFFICE

2,167,184

LIGHTING UNIT

Paul D. Phillips, Elmhurst, Ill., assignor to Benjamin Electric Mfg. Company, Des Plaines, Ill., a corporation of Illinois

Application December 3, 1936, Serial No. 113,972

8 Claims. (Cl. 240—11.2)

This invention relates to lighting units, and more particularly to portable lighting units for use in hazardous locations such as grain elevators and the like, where the air is dust-laden and likely to be explosive.

This application is a continuation in part of my copending application Serial No. 31,960, filed July 18, 1935.

In certain locations, particularly such as grain elevators, it is desirable that the light source should be completely enclosed to prevent dust coming in direct contact with hot surfaces, and it is also desirable that the structure should be such that all exposed surfaces shall be at a comparatively low temperature and that the fixture be so constructed that no appreciable quantities of dust will accumulate thereon.

Rubber-covered conductors or cables are usually used in wiring such fixtures, and it is required that these conductors be kept at a comparatively low temperature, ordinarily not more than 120°. It is therefore an object to provide a fixture which may be conveniently installed and easily wired in such a manner that the rubber-covered conductors leading to the terminals are protected from excessive temperatures.

It is also an object of the present invention to provide a dust-proof lighting fixture having all of the above noted desirable characteristics and in which the outer contour is such that excessive quantities of dust will not accumulate thereon.

A further object is to provide such a unit in which the temperature on the outside of the unit is below the charring point of grain dust and the like.

It is also an object to provide a dust-proof lighting fixture in which the lamp chamber is sealed off from the wiring terminal chamber, and in which means is provided to prevent excessive heat transfer from the light source to the wiring terminals.

A further object is to provide such a unit in which provision is made for connecting a 3-wire cable, one of which wires affords the ground connection, and in which all of the wires leading to the terminals are protected from excessive high temperatures.

It is also an object to provide a unit of the character described in which provision is made for supporting the unit to enable it to be lowered into a bin or the like without making use of the conductor cable as a support.

A further object is to provide such a unit in which a suitable guard is provided to protect the glass front covering from the surface on which it

might be set, to prevent igniting any material on this surface in case the lamp is left burning.

Provision is also made whereby the device may easily be polarized when desired.

Further objects will be apparent from the specification and the appended claims.

In the drawings:

Figure 1 is a vertical axial section of the unit and illustrates one embodiment of the invention.

Fig. 2 is a top plan view of the unit shown in Fig. 1 with the hood removed, and illustrates the method of wiring the fixture.

Fig. 3 is a side elevation of the sealing plug.

Fig. 4 is a top view of the unit with the hood secured thereon.

Fig. 5 is a fragmentary sectional view through one of the wiring terminals, and taken on a line substantially corresponding to line 5—5 of Fig. 2.

Fig. 6 is a fragmentary axial sectional view of a slightly modified embodiment of the invention.

Fig. 7 is a top view of the embodiment illustrated in Fig. 6 with the hood removed.

Referring to the drawings in detail, the embodiment illustrated in Figs. 1 to 5, inclusive, comprises a concave parabolic reflector 1 which

may be of polished "Nicral" or any suitable material, and provided with a cylindrical neck or extension 2 secured thereto as illustrated, and arranged to receive the stem of the usual electric bulb 3.

The reflector neck 2 is internally flanged at its upper end as shown, and a socket 4 is secured thereto as illustrated by means of screws or bolts 5.

This socket is preferably a waterproof molded composition receptacle and is provided with the usual terminals 6, only one of

which is shown, the other terminal being on the opposite side of the socket. An asbestos gasket 7 is secured between the flange of the extension 2 and the socket 4, thereby providing a substantially air-tight connection and heat insulation.

By means of this construction, the reflector 1 surrounds the bulb portion of the lamp, and is provided with an opening through which the lamp stem may be inserted upwardly into the socket, and the upper end of the reflector is spaced a substantial distance below the lower end of the socket by means of the extension 2.

A sheet metal concave casing 8 surrounds the reflector and socket, and is preferably substantially co-axial therewith. The lower edge of the

casing 8 snugly fits the reflector 1, and the reflector may be secured therein by means of rivets 9, or in any other suitable manner, whereby a substantially dust-proof joint is provided.

The lower rim of the casing 8 projects out-

55

wardly and is provided with a downwardly-extending flange 10 providing a space between the rim of the reflector 1 and the flange 10, wherein a gasket 11 is mounted to provide a dust-proof packing between a lens or glass cover 12 and the casing. The lens is held in position against the gasket by means of an annular channeled clamping band 13, the ends of which are secured in clamping relation by means of a screw 14 co-operating with studs 15 on the band. In order to hold the gasket in position when the lens is removed, the downwardly-extending flange 10 may be indented at various points by means of a prick punch to force portions of this flange into the gasket.

A wire guard 16 is secured to the clamping band 13 in any suitable manner, as by welding, to form an integral part thereof and to be removable therewith. The casing 8 diverges upwardly away from the reflector to provide a substantial heat-insulation space between the reflector and casing, and also so that the contour may be comparatively smooth and inclined at such a steep angle that dust will tend to slide off the surface and not accumulate thereon. The casing is provided with a restricted portion extending upwardly above the socket 4 and spaced therefrom and provided with an inturned flange 17.

An insulating block 18, preferably of wood, is secured to this flange as illustrated, by means of screws 19. Gaskets 20, made of press-board or similar material, are preferably inserted between the flange 17 and the spacer block 18. The block 18 is provided with a protecting ferrule 21, the lower end of which is spaced from the upper end of the casing 8 and secured to the block 18 by rolling the lower edge into a groove 22. The spacing of the ferrule from the casing 8 is to minimize heat transfer therebetween. A comparatively narrow metal strip 23 is secured to the casing 8, preferably by spot-welding, and extends upwardly to overlap the ferrule 21, and is retained in electrical contact therewith by means of a screw 24. This strip is for the purpose of grounding the entire unit, as will be explained later.

The insulating block 18 is provided with a chamber 25 therein having a restricted eccentric passage 26 communicating with an axial depression 27 formed in the upper end of the block. The passage 26 is for the purpose of enabling the interior of the fixture to be filled with a suitable insulating material 28. This insulating material 28 may be of any suitable type, preferably so-called exploded mica. After the unit has been filled with the insulating material 28, the eccentric passage 26 is closed by means of an insulating plug 29 which is also preferably made of wood. This plug is illustrated in detail in Fig. 3, and is provided with a flange 30 having a transverse groove 31 therein to receive a wiring cable 32, which is preferably a 3-wire cable.

After the unit is filled with insulating material 28, as illustrated, the plug 29 is inserted in the eccentric opening 26 and preferably cemented therein by any suitable cement, and secured by means of a screw 33, preferably inserted at the joint as illustrated. The plug is eccentrically positioned in order to provide a narrow wiring space in the depression 27 on the left-hand side as illustrated at 34. The space at this point is just sufficiently large to receive the conductors 35, 36, and 37, forming a part of the cable 32, and the space gradually increases in width toward

the right-hand side of the depression 27 as illustrated, to receive terminals 38 and 39, as illustrated in Figs. 2 and 5. These terminals are preferably in the form of screws 38 (Fig. 5), secured in the insulating block 18 and provided with openings in their upper end as illustrated, into which the bare ends of the conductors are inserted and soldered. It will be obvious that ordinary binding terminals may be used if desired.

The screws 38 and 39 extend into the chamber 25 of the insulating block 18, and elongated, flexible heat-proof conductors 40 are electrically secured thereto and to the terminals 6 on the socket 4. These conductors 40 are asbestos covered and are entirely within the space between the reflector and casing, and of sufficient length to permit expansion and contraction by changes in temperature, and to prevent their becoming loosened or broken by vibration or shock.

The ground wire 37 is secured to the inturned flange 41 of the ferrule 21 by means of a binder screw 42. It will therefore be seen that after the unit is properly wired, the entire device is suitably grounded. A hood 43 is secured to the insulating block 18 by means of screws 44 extending through the flange 41 and into the wood block 18. The hood 43 is provided with an upwardly-extending tubular portion 45, through which the conductor cable extends, and which is provided with a suitable packing gland 46. The hood is also provided with a handle or loop 47, by which the fixture may be supported by means of a flexible cable, or in any other suitable manner, and whereby the fixture will hang substantially vertically when so supported.

It is desirable that fixtures of this type should be polarized in wiring, and therefore the conductors 35 and 36 and the ground wire 37 are preferably of different colors for that purpose. After the fixture has been properly wired, as previously described, a disc 48 is secured to the plug 18 as illustrated in Figs. 1 and 2, by means of screws 49 extending into the plug. This disc is in a position to clamp the cable 32 in the groove 31 and to clamp the conductors extending therefrom in the narrow space 34 as illustrated, the conductors extending therefrom to the proper terminals as illustrated.

The upper side of the disc 48 is provided with a diagram and suitable legends such as shown in Fig. 2, which illustrates the manner of wiring in order to suitably polarize the fixture. This diagram may be stamped or printed directly on the metal disc, or may be printed on a paper or other fabric adhesively secured to the disc.

It will be apparent that the construction of the unit is such that dust cannot enter the lamp enclosure, and that the contour of the casing tends to prevent dust from settling thereon. The temperature of the outside of the unit is relatively low because of the insulating material used and the air spaces between the particles of insulation.

The lamp chamber is a considerable distance from the hood, and is completely sealed off from the wiring terminal and effectively heat-insulated from the casing. Means is provided for grounding all metallic parts of the unit, and dust is effectively prevented from entering the hood. Provision is also made whereby the unit may be lowered into a bin or the like without making use of the conductor cable as a support, and when the unit is placed on the floor the wire guard will support it in upright position and far enough from

the floor to prevent danger of igniting the material underneath the lens.

Figs. 6 and 7 illustrate an embodiment of the invention wherein certain parts are omitted, such as the reflector extension neck, and the socket is mounted directly on a partition between the casing and hood. In this embodiment, the reflector is provided with a central opening 50 to receive the bulb and shock-absorbing springs 51 are arranged to engage the bulb and lessen the harmful effects of vibration. The casing 8a is provided with an inwardly-extending flange 52, to which are clamped gaskets 53 and 54, which are held in the position shown, to form an insulating partition by means of screws 55 extending through suitable registering holes in the hood, gaskets, and flange, and threaded into a metal clamping washer 56. The gaskets are provided with registering openings affording access to wiring terminals 57 and 58. A ground terminal 59 is secured to the casing flange and provided with an up-turned portion engaging the hood 60. This hood may be similar in construction to that previously described.

In the embodiment illustrated in Fig. 1 it is sometimes desirable to provide an asbestos washer 61 around and snugly fitting the bulb 3. This washer is preferably reinforced by means of a metallic washer 62 secured by means of rivets. The washer is removably held in the extension 2 by means of indentations made in the hood by means of a prick punch.

Further modifications will be apparent to those skilled in the art, and it is desired, therefore, that the invention be limited only by the prior art and the scope of the appended claims.

Having thus described this invention, what is claimed and desired to be secured by Letters Patent is:

1. A portable pendant dust-proof floodlighting fixture comprising a lamp socket for supporting a lamp with its axis in substantially vertical position, a concave reflector surrounding the bulb portion of the lamp and having an opening through which the lamp may be inserted upwardly into the socket, the upper end of said reflector being spaced a substantial distance below the lower end of the socket, a lens extending across the light aperture, a metal guard extending across and in front of the lens, a sheet metal concave casing surrounding the reflector and socket and coaxial therewith, a hood above said casing and socket having an opening for the feed wires, a sealing partition between the lamp chamber of the casing and the chamber of the hood having an opening affording access to the wiring terminals of the socket from above, a wiring terminal in said hood for connection with a ground wire electrically connected with said casing, and means for electrically connecting said wiring terminal with the hood comprising a spring clip bearing on the inside of the hood.

2. A portable pendant dust-proof floodlighting fixture comprising a lamp socket for supporting a lamp with its axis in substantially vertical position, a concave reflector surrounding the bulb portion of the lamp and having an opening through which the lamp may be inserted upwardly into the socket, the upper end of said reflector being spaced a substantial distance below the lower end of the socket, a substantially dust-tight enclosure for said socket and reflector comprising a casing and a lens extending across the light aperture, the lower annular edge of the reflector being secured to and supported by the

lower annular edge of the casing, the wall of the casing being coaxial with the reflector and diverging upwardly away from the reflector to provide a substantial heat insulation space between the reflector and casing, and a substantially dust-tight hood detachably secured to said enclosure above the socket and having an opening for the feed wires for the socket.

3. A portable pendant dust-proof floodlighting fixture comprising a lamp socket for supporting a lamp with its axis in substantially vertical position, a concave reflector surrounding the bulb portion of the lamp and having an opening through which the lamp may be inserted upwardly into the socket, the upper end of said reflector being spaced a substantial distance below the lower end of the socket, a substantially dust-tight enclosure for said socket and reflector comprising a casing and a lens extending across the light aperture, the lower annular edge of the reflector being secured to and supported by the lower annular edge of the casing, the wall of the casing being coaxial with the reflector and diverging upwardly away from the reflector to provide a substantial heat insulation space between the reflector and casing, a substantially dust-tight hood detachably secured to said enclosure above the socket and having an opening for the feed wires for the socket, said lens being convex and extending below the lower edge of the casing, and a metal guard secured to the lower edge of the casing and having a substantially horizontal portion extending across below the lens for resting on the floor to support the fixture in upright position with the convex lens out of contact with the floor.

4. A dust-proof lighting unit comprising a concave reflector, a socket for supporting an electric bulb in axial relation in said reflector, an elongated concave casing surrounding said reflector in axial relation and arranged to form a dust-proof heat-insulating space therebetween, the upper end of said casing being of reduced diameter and having an opening therethrough, an insulating block on said casing and having a passage therethrough forming a continuation of said insulating space through which passage heat insulating material may be inserted into said heat insulating space, said space being substantially completely filled with comminuted heat-insulating material, wiring terminals on said block, a plug sealing said passage and forming a guide for conductors to said terminals, elongated heat-proof conductors between said terminals and said socket, and a dust-proof hood on said block and covering said terminals.

5. A dust-proof lighting unit comprising a reflector having a socket for supporting a light bulb, a lens forming a dust-proof cover for said reflector, a sheet metal casing forming an insulating space around said reflector, said casing having a reduced portion extending above said socket and having an inturned flange, a wood block secured to said flange and forming an extension of said insulating space, a ferrule on said block and spaced from said casing but having a comparatively small ground connection therewith, wiring terminals on said block and electrically connected with said socket, a removable dust-proof hood covering said wiring terminals and in grounded relation with said ferrule, and a ground wire terminal connected to said ferrule.

6. A dust-proof lighting unit comprising a reflector having a socket for supporting a light bulb, a lens forming a dust-proof cover for said re-

5. reflector, a sheet metal casing forming an insulating space around said reflector, said casing having a reduced portion extending above said socket and having an inturned flange, a wood block secured to said flange and forming an extension of said insulating space, comminuted heat-insulating material in said space, a ferrule on said block and spaced from said casing but having a comparatively small ground connection therewith, 10 wiring terminals on said block and electrically connected with said socket, a removable dust-proof hood covering said wiring terminals and in grounded relation with said ferrule, and a ground wire terminal connected to said ferrule.
15. 7. A portable pendant dust-proof floodlighting fixture comprising a lamp socket for supporting a lamp with its axis in substantially vertical position, a concave reflector surrounding the bulb portion of the lamp and having an opening through which the lamp may be inserted upwardly into the socket, a substantially dust-tight enclosure for said socket and reflector comprising a casing and a lens extending across the light aperture, the lower annular edge of the reflector being secured to and supported by the lower annular edge of the casing, the wall of the casing being coaxial with the reflector and diverging upwardly away from the reflector to provide a substantial heat insulating space between the reflector and casing, said casing having an 20 opening at its upper end, an insulating base extending across said opening and having a pas-
20. 25. 30.

sage therethrough through which particles of insulating material may be introduced into said heat insulating space, a closure for said passage, wiring terminals on said base, and a substantially dust-tight hood detachably secured to said insulating base and having an opening for the feed wires for said terminals.

8. A portable pendant dust-proof floodlighting fixture comprising a lamp socket for supporting a lamp with its axis in substantially vertical position, a concave reflector surrounding the bulb portion of the lamp and having an opening through which the lamp may be inserted upwardly into the socket, the upper end of said reflector being spaced a substantial distance below the lower end of the socket, a substantially dust-tight enclosure for said socket and reflector comprising a casing, a heat insulating block secured to the upper end of the casing and a lens extending across the light aperture, the lower annular edge of the reflector being secured to and supported by the lower annular edge of the casing, the wall of the casing being coaxial with the reflector and diverging upwardly away from the reflector to provide a substantial heat insulation space between the reflector and casing, wiring terminals above said heat insulating block and electrically connected with said socket, and a substantially dust-tight hood detachably secured to said enclosure above the socket and having an opening for the feed wires for the socket.

PAUL D. PHILLIPS.
